US00D438464S

(12) **United States Design Patent** (10) Patent No.: **US D438,464 S**
Newhouse et al. (45) Date of Patent: ** Mar. 6, 2001

(54) **CONTAINER AND DISPENSER ASSEMBLY
FOR TOOL BITS**

3,179,244 * 4/1965 Kuhn 206/216
5,396,985 * 3/1995 Seki 206/457

* cited by examiner

Primary Examiner—Philip S. Hyder

(74) Attorney, Agent, or Firm—Maginot, Addison & Moore

(75) Inventors: **Debbie A. Newhouse**, Prospect, KY
(US); **Mathew S. Taylor**, Shelby, OH
(US)

(73) Assignee: **Credo Tool Company**, Woodburn, OR
(US)

(**) Term: **14 Years**

(21) Appl. No.: **29/111,240**

(22) Filed: **Sep. 23, 1999**

(51) LOC (7) Cl. **09-03**

(52) U.S. Cl. **D9/417; D8/71; D3/273**

(58) Field of Search D3/273; D9/416,
D9/417, 433, 414; 229/113, 213, 114, 214
